AUTOGRAPHIC REGISTER

Albert W. Metzner, Dayton, Ohio, assignor to The Standard Register Company, Dayton, Ohio, a corporation of Ohio

Application August 30, 1943, Serial No. 500,463

14 Claims. (Cl. 282—21)

This invention pertains to autographic registers utilizing continuous series connected detachable form stationery, and more particularly to strip feeding means therefor adapted to intermittently advance the record strips through successive steps of predetermined extent by a "push-pull" action.

Briefly stated, there is herein contemplated a manually reciprocatory frame movable to and fro in a substantially horizontal plane above a writing tablet over which succeeding portions of continuous strips of record material are advanced past the writing position. The reciprocatory frame positively engages with the record material at the limit of its retractive movement, and upon advancement carries the record material with it throughout its full stroke. At the forward limit of its stroke the record material is temporarily detained to prevent retrograde movement thereof while the actuating frame is being idly returned preparatory to a succeeding operation. The interengagement of the reciprocatory frame with the record material and the retention of the latter at the limit of each advance movement thereof, is preferably effected by engagement of pins or studs in correspondingly positioned holes in the record material. These holes may be file holes or binder holes suitably positioned in the record material, or may be holes specially provided in the margins or elsewhere in the stationery for the particular purpose.

The object of the invention is to improve the construction as well as the means and mode of operation of strip feeding means for continuous record strips, whereby such devices may not only be economically manufactured, but will be more efficient in use, accurate in operation, uniform in action, having relatively few parts, and be unlikely to get out of repair.

A further object of the invention is to provide a strip feeding device capable of accurately advancing strips of any width measured distances smoothly and evenly without mutilation.

A further object of the invention is to provide a strip feeding apparatus which may be equally easily and conveniently manipulated by either right or left handed operators with minimum effort.

A further object of the invention is to provide a reciprocatory pin type feeding unit for continuous form stationery.

A further object of the invention is to provide an apparatus of the character described, having the advantageous structural features, the meri-

torious inherent characteristics, and the mode of operation herein set forth.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

For illustrative purposes, but without intent to unduly limit the application or scope of the invention, it is herein illustrated embodied in an autographic register of the desk type, of which Fig. 1 is a perspective view, showing the reciprocatory feeding frame and the record material to be advanced, both in the normal or record receiving position.

Fig. 2 is a fore and aft sectional view on line 2—2 of Fig. 1.

Fig. 3 is a transverse sectional view on line 3—3 of Fig. 1.

Fig. 4 is an enlarged detail sectional view on line 4—4 of Fig. 1.

Fig. 5 is a detail perspective view illustrating the feeding engagement of the reciprocatory frame with the record material.

Fig. 6 is a similar detail perspective view, showing the advanced portion of record material anchored against retrograde motion while the actuating frame is shown being returned.

Fig. 7 is a detail perspective view of a portion of the actuator slide viewed from the under side.

Fig. 8 is a perspective view of the assembled apparatus embodying a modification for utilizing file holes at the head of each form for feeding purposes.

Fig. 9 is a sectional view on line 9—9 of Fig. 8. Figs. 10 and 11 are detail plan views showing a method of utilizing the same holes in the record material for both feeding and holding purposes.

Fig. 12 is a detail sectional view on line 12—12 of Fig. 10.

Fig. 13 is a perspective view of a packet of conventional marginally punched record material, such as is adapted for pin wheel or pin chain feed, but which is usable in the present apparatus.

Fig. 14 is a plan view of interconnected portions of conventional record forms having terminal file holes with which the present feeding and detent devices are engageable.

Fig. 15 is a detail elevational view of the means for deflecting the record material into detent en-

gagement with the retaining pins at the limit of the feeding movement.

Like parts are indicated by similar characters of reference throughout the several views.

In the drawings there is illustrated a desk type of register to be positioned in the top of a desk, counter, table, or the like, and in order that the register may harmonize in appearance with its supporting structure, it is shown as constructed of wood. It is to be understood, however, that it may be constructed of metal parts. The structure illustrated may be utilized in a portable register, in which event it will be mounted as the top of a box or cabinet for a supply of stationery to be progressively advanced therefrom over the writing tablet.

Referring to Fig. 1 of the drawings, 1 indicates the desk or counter top, having therein an opening 1a in which the present register device is installed. The assembly includes a base 2 having upstanding rabbeted margins 3, which overhang and rest upon the desk or counter top 1 about the margin of the opening 1a in which the present structure is fitted. In the event that a portable structure is provided, the assembly overlies the box or cabinet thereof with the rabbeted margins 3 resting on its side walls. Disposed upon the base 2 in inwardly spaced relation with the margins 3 is tracker board 4, over which the continuous form stationery 5 is drawn through a slot 6 at its rear from a supply compartment in the desk or counter, or within the cabinet, beneath the assembly.

The rear portion of the tracker board 4 has a sheet 7 of metal, or preferably glass, inlaid therein to afford a hard surfaced writing tablet, upon which the superposed portions of the record material are inscribed. The spaced relation of the upstanding rabbeted margins 3 and tracker board 4 affords therebetween parallel channels 8 adjacent the opposite sides of the assembly, in which are stationarily disposed longitudinally grooved slide bearings or tracks 9. Mounted on the slide bearings 9 for to and fro reciprocation relative thereto are actuator slides 10, having on their under sides longitudinal tongues 11 which fit within the grooves 12 of the slide bearings or tracks 9. The top surfaces of the slides are rabbeted with the elevated face thereof flush with the top plane of the tracker board 4. In the forward end of each slide 10 is a forwardly inclined pin 13 engageable in a marginally positioned hole in the record material to be advanced. Such hole may be one of a marginally punched conventional strip of series connected detachable form stationery, or may be a hole especially provided in the record material. The pins 13 are inclined forwardly in the direction of advancement of the record material. The pins act somewhat in the manner of ratchet teeth in engaging and advancing the record material as they move in one direction, i. e., forwardly, and easily withdrawn from the engaged holes in the record material upon retraction of the slides.

The reciprocatory slides 10 at the opposite sides of the assembly are interconnected by a U shaped frame 14 which rests on the slides and is connected thereto by dowel pins 15, which engage in corresponding holes in the slides. The transverse rearward bar 16 of the frame 14 provides a convenient handle portion to be grasped by the operator while pushing the frame 14 forward and with it the slides 10. During forward movement the pins 13 are engaged in marginal

holes in the record material. While pulling the frame and slides rearwardly idly for reengagement of the pins with other holes in the record material at spaced intervals, due to their inclination the pins travel past the holes without engaging therein.

Mounted in laterally offset portions 17 of the tracker board 4 beyond the range of travel of the slides 10, are other forwardly inclined stationary pins 18. As the sliding frame and the forward end of the record material advanced thereby reach the limit of their range of travel, other holes closely adjacent to the holes engaged by the pins 13 are brought into registry with the forward ends of the inclined stationary pins 18. On the under sides of the lateral arms of the reciprocatory frame 14 closely adjacent to the positions of the pins 13 in the slides 10 when the frame is coupled therewith, are dependent ledges 19 which extend somewhat below the tops of the pins, and tend to press the margins of the record material down into position where the pins 13 enter the marginal holes therein. At the limit of forward movement of the frame and slides, the paper retaining ledges 19 extend slightly beyond the stationary pins 18 and serve the same purpose of depressing the margins of the record material below the tops of the pins 18, which engage in the holes thereof to hold the record material in advanced position and prevent its retraction as the frame and slides are drawn rearwardly.

Upon retraction of the slides, the pins 13 are also retracted from engagement with the record material, which is easily effected due to the inclination of the pins, thus leaving the record material securely hooked over the stationary inclined pins 18, which as a result of their inclination and the retractive tendency of the record material maintain their engagement therewith. The advancement of the record material by movement of the frame 14 and pin carrying slides 10 carries with them the inscribed portion of the record material and draws a succeeding blank form from the source of supply through the slot 5 into inscribing position on the writing tablet. The subsequent idle retraction of the actuator frame 14 and strip feeding slides 10, leaves the previously inscribed portion of the record material hooked on the stationary pins 18. Upon return of the actuator frame and strip feeding slides to their normal or retracted position, the previously advanced inscribed portion of the record material may be manually disengaged from the holding pins 18 and torn off, preparatory to the next operation. The actuator frame 14 is easily detachable from the strip feeding slides, as indicated by dotted lines in Figs. 2, 3 and 4 to facilitate loading and initial placement of the margins of the record material in position for engagement with the pins 13 beneath the overhanging inner margins of the arms of the actuator frame 14. At the rear end of the assembly is a removable stop rail 20 overlying the record material supply slot 5, against which the actuator frame 14 abuts at the limit of its retractive movement. This rail is engaged with the main structure by dowel pins 21 and is also readily removable to facilitate initially threading the record material through the slot 5 from the source of supply to the top of the writing tablet. At its forward limit of travel the sliding actuator frame and strip feeding slides 10 are arrested, when a predetermined length of record material has been advanced, by engage-

ment with a lateral offsets or shoulders 22 of the tracker board.

The inclined pins 13 and 18 may be so located that they engage different relatively spaced holes in the record material, as is shown in Fig. 5. The pins 13 may engage feed holes in the record material in spaced relation with the end of the record strip to be advanced, and the detent pins are so located that at the limit of the advance movement they engage other holes intermediate those engaged by the pins 13 and the terminal edge of the strip, but not necessarily the holes closest to the end of the strip as shown. As an alternate construction, both the feeding pins 13 and the detent pins 18 may be made to engage in the same holes in either the margins of the record material or in the medial body portion thereof.

Such construction is illustrated in Figs. 8, 10, 11 and 12, wherein the apparatus is illustrated as engageable with file holes 23 at the heads of the forms. The general construction is the same as that before described, except that the slides 10 of the actuator frame are interconnected at their forward ends by a cross bar 24, and the forward portion of the tracker board 4 is cut away at 25 to enable to and fro motion of the cross bar 24 beneath the plane of the record strip. The cross bar 24 is formed with a medial rectangular notch 26. The end of the tracker board beyond the depression 25 is provided with a corresponding rearwardly projecting extension 27 which projects within the rectangular notch 26 of the cross bar 24 when the actuator frame is at the advance limit of its range of movement. The pins 13a and 18a in this instance are halved longitudinally. Each pin is flat on one side and of convex tapered or conical shape on its opposite side. The shape of the pins is such that when two such pin portions, i. e., a half pin 13a and a half pin 18a, are positioned side by side, they together make a complete conical split pin.

The half or split pins 13a are carried in spaced relation upon the cross bar 24 of the reciprocatory actuator frame, and when the frame is retracted they engage in the spaced file holes 23. Being flat on one side and convex on their opposite sides, they occupy only one-half of each file hole 23. Preferably, but not necessarily, the half pins 13a are positioned to occupy the outer halves of the respective file holes 23. The detent pins 18a are of the same shape, but disposed in reverse relation. The pins 13a being engaged in the file holes serve to advance the record material as the actuator frame is advanced, until at the limit of the range of travel the pins 13a assume positions along side the pins 18a and in registry therewith. The half pins 13a and 18a thus conjointly correspond to a complete pin and the half pins 18a engaging in the same file holes 23 with the feeding pins 13a completely fill such file holes. Upon retraction of the actuator frame, the half pins 13a, due to their inclination, readily withdraw from the file holes 23, leaving the pin halves 18a securely hooked therein, and from which, due to their inclination, the record strip is not likely to be accidentally disengaged. While such divided pin construction engageable in the same hole in the record material is illustrated only in relation to file holes 23 in the body of the record form, it is to be understood that the same feature may be embodied in the construction illustrated in Figs. 1, 5 and 6, wherein the pins engage in marginal holes in the record material. Instead of causing the pins 13 and 18

5 to engage different relatively spaced holes, these pins too may be split and made to simultaneously engage in the same marginal hole at the forward limit of travel of the actuator slide, whereby 10 the strip will be detained by one of the half pins while the other is withdrawn for reengagement with a succeeding record form.

15 From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

20 While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

25 Having thus described my invention, I claim:

30 1. An autographic register, including a writing tablet over which a continuous strip of series connected detachable form stationery having therein a series of longitudinally spaced feed holes is progressively advanced past a record receiving position, a reciprocatory slide, a forwardly inclined feeding pin carried by the reciprocatory slide and engageable in a hole in the stationery strip upon movement of the slide in one direction to advance the strip in unison therewith, and automatically retractable out of the hole in the strip upon retraction of the slide, and a forwardly inclined pin stationarily mounted in the structure engageable in a hole in the strip at the limit of advancement of the latter under influence of the reciprocatory slide, over which the strip becomes engaged to prevent retrograde movement of the advanced portion of the strip upon retraction of the slide.

35 45 50 55 60 65 70 75 2. A strip feeding apparatus for advancing a continuous strip of material having longitudinally spaced holes therein through successive step by step movements of predetermined extent, including a pair of inclined members engageable in holes in the strip, one of which is fixed and the other movable toward and from said fixed member and a reciprocatory carrier for the movable member, the construction and arrangement being such that upon movement of the carrier in a direction coincident with the inclination of said members, the movable member will engage in a hole in the strip to advance the strip in unison with the carrier, at the limit of which movement the advanced portion of the strip is engaged with the stationary member to hold the advanced portion of the strip against retrograde movement during retraction of the carrier.

3. An autographic register, including a writing tablet over which a continuous strip of series connected detachable forms having therein a series of longitudinally spaced cut outs is intermittently advanced past a record receiving position, a reciprocatory actuator subject to manual push pull operation, an inclined pin on the reciprocatory actuator having thrust engagement in a hole in the strip when moved in the direction of inclination of the pin, to effect unison

movement of the strip, and readily disengageable from the hole in the strip when moved in the opposite direction, and a correspondingly inclined stationary pin in the path of movement of the strip over which a hole in the strip is positioned at the limit of movement of the strip and in which the stationary pin has thrust engagement upon slight retrograde movement of the strip to hook the latter thereon, and resist further retrograde movement thereof.

4. An autographic register, including a writing tablet over which a continuous strip of record material, having longitudinally spaced holes therein, is advanced past a record receiving position, a pair of laterally spaced parallel slides mounted at opposite sides of the writing tablet, forwardly inclined pins carried by the slides and engageable in marginal holes in the strip upon their movement in one direction, and readily retractable from such holes on retraction of the slides, detent means engageable with the advanced portion of the strip to prevent retrograde movement thereof, while the slides are being retracted, and a U shaped frame overlying the slides and detachably engageable therewith, and intercoupling the slides for unison reciprocatory movement.

5. A strip feeding apparatus wherein a continuous strip of material having longitudinally spaced configurations is progressively advanced through step by step movement, including a reciprocatory slide member, a traveling forwardly inclined strip engaging member carried thereby, engageable with a configuration of the strip upon forward movement of the slide in one direction, to correspondingly advance the engaged strip, and automatically disengageable therefrom upon retractive movement of the slide, a stationary forwardly inclined strip engaging member relative to which the strip is advanced incident to the forward movement of the slide, and automatically engageable with a configuration of the strip to resist retrograde movement of the strip incident to retraction of the slide, the strip being automatically disengageable from the stationary strip engaging member upon further advance movement of the strip.

6. A strip feeding apparatus wherein a continuous strip of material having therein longitudinally spaced configurations is progressively advanced through a succession of step by step movements, including a pair of ratchet like members engageable with the configurations of the strip, one of the ratchet like members being stationary and by its engagement with the strip preventing retrograde movement thereof, the strip being automatically disengageable therefrom by initial advance movement of the strip, the other ratchet like member being movable relative to the stationary ratchet like member and engageable with configurations of the strip to advance the strip relative to the stationary strip engaging member, during its movement in a forward direction and automatically disengageable therefrom upon retraction of said member, and a reciprocatory carrier for the movable member.

7. A strip feeding apparatus wherein a continuous strip of material having therein longitudinally spaced holes is progressively advanced through successive step by step movements, including a pair of pins inclined in the direction of travel of the strip engageable in the holes of the strip and movable one relative to the other in alignment with the strip, a traveling carrier for the movable pin capable of to and fro mo-

tion, and a stationary support for the other pin, the construction and arrangement being such that upon movement of the carrier in the direction in which the pin carried thereby is inclined, said pin will engage a hole in the strip to advance the strip in unison therewith, at the limit of which movement a hole therein is engaged by the stationary pin to prevent retrograde movement of the strip upon retraction of the carrier, the movement of which automatically withdraws the inclined feeding pin from engagement with the strip, preparatory to its reengagement therewith for further movement of the strip by which the strip is automatically disengaged from the stationary inclined pin.

8. A strip feeding apparatus wherein a continuous strip of material having longitudinally spaced configurations is progressively advanced through successive step by step movements, including a stationary support, a reciprocatory slide mounted thereon, a feeding stud carried by the slide automatically engageable with a configuration of the strip to advance the strip in unison with advancement of the slide, upon movement of the latter in one direction and automatically disengageable therefrom upon movement of the slide in the reverse direction, a detent stud carried by the support to prevent retrograde movement of the strip upon retraction of the strip at the limit of each forward step by step movement of strip and automatically disengageable therefrom upon initiation of each forward step by step movement of the strip, and a deflector automatically deflecting the strip into engagement with said detent stud as the strip reaches the limit of each forward step by step movement.

9. A strip feeding apparatus wherein a continuous strip of material having longitudinally spaced configurations is progressively advanced through a step by step movement, including a traveling feeding pin and a stationary detent pin both engageable with configurations of the strip, a reciprocatory carrier for the feeding pin, a stationary support for the detent pin, and guide means for deflecting the strip out of its normal plane into interengaging relation with at least one of the pins at the limit of a predetermined range of movement thereof.

10. A strip feeding apparatus wherein a continuous strip of material having longitudinally spaced configurations is progressively advanced through a step by step movement, including a split pin, each half of which is engageable with a configuration of the strip, one half the split pin being movable in unison with advancement of the strip into registry with the other half of the split pin, the latter half thereof being engageable with a configuration of the strip to detain the strip in its advanced position, a traveling carrier for one half of the split pin and a stationary support for the other half of the split pin.

11. A strip feeding apparatus wherein a continuous strip of material having longitudinally spaced configurations is progressively advanced through a step by step movement, including a pair of pin members each being flat on their adjacent sides and convex on their outer sides, adapted for relative movement of one into and out of registering relation with the other, a reciprocatory slide upon which one of the pin members is carried and a stationary support upon which the other pin member is mounted, the construction and arrangement being such that the pin member carried upon the slide is engageable with a configuration of the strip to advance the

strip a predetermined distance and the stationary pin member is engageable with a configuration of the strip at the limit of its advancement to prevent retrograde motion of the strip.

12. A strip feeding apparatus for progressively advancing a continuous strip of material having longitudinally spaced holes therein through successive step by step movements, including a reciprocatory actuator for advancing the strip measured distances, a stationary strip engaging pin located in the path of the strip and inclined in the direction of advancement of the strip engageable in a hole therein at the limit of each advance movement of the strip to prevent retrograde movement thereof and from which the strip is automatically disengageable by its initial further advancement under influence of the actuator in the direction in which the pin is inclined.

13. A strip feeding apparatus for progressively advancing a continuous strip of material having longitudinally spaced holes therein through successive step by step movements, including a reciprocatory actuator for advancing the strip measured distances, and a feed pin carried by

the actuator in the path of advancement thereof and inclined in the direction of advancement of the strip and engageable in a hole in the strip during the movement of the actuator in one direction, said pin being automatically retractable from said hole in the strip upon retraction of the actuator, and a detent engageable with the strip at the forward limit of its movement preventing retrograde movement of the strip.

14. A strip feeding apparatus for progressively advancing a continuous strip of material having longitudinally spaced holes therein through successive step by step movements, including a reciprocatory actuator for advancing the strip measured distances, a pair of strip engaging pins located in the path of travel of the strip and both inclined in the direction of advancement thereof and alternately engageable in holes in the strip, one of the pins being movable to and fro in unison with the actuator, to advance the strip, the other pin being stationary and effective to retain the strip in its advanced position and prevent retraction thereof.

ALBERT W. METZNER.
